UNITED STATES PATENT OFFICE

2,435,001

POLARIZED ELECTROMAGNETIC RELAY

Oscar S. Field, Rochester, N. Y., assignor to
 General Railway Signal Company, Rochester,
 N. Y.

Original application October 14, 1940, Serial No.
 361,060, now Patent No. 2,376,534, dated May
 22, 1945. Divided and this application April
 17, 1945, Serial No. 588,749

3 Claims. (Cl. 175—335)

1

This invention relates to relays and/or electroresponsive devices which will be actuated only if current of the proper character and polarity flows simultaneously in two circuit portions. This application is a division of my prior application Ser. No. 361,060, filed October 14, 1940, which has resulted in a Patent No. 2,376,534, dated May 22, 1945.

Multiple winding relays and electromagnets employing two windings such as devices of the dynamometer type are well known but by reason of their high reluctance when no iron is used therein are very inefficient. If such electromagnets or relays are provided with a considerable amount of soft iron in either or both of their windings to improve their efficiency there is a danger of actuation of the electromagnet or relay in response to the energization of only one of their windings to an excessive extent.

In view of the foregoing it is proposed in accordance with the present invention to provide an electromagnet for an electro-responsive device employing a multiple closed magnetic core structure so arranged that each of the two closed cores serves as a very effective magnetic shunt for the other core and to provide each such closed core with its individual winding.

Another feature of the present invention follows from the fact that if the relative polarity of one of the two circuits or circuit portions for energizing the two windings is opposite from what was intended, the electro-responsive device will not respond, and thus the structure may be used as a polar relay or polar electromagnet.

As another object of the present invention it is proposed to employ a full-wave rectifier when the electromagnetic structure is to be used as a direct current polarity responsive device by having one of the two windings energized from the rectifier the input terminals of which receive their energy from the circuit for energizing the other winding.

Other objects, purposes and characteristic features of the invention will in part be pointed out in the specification hereinafter and will in part be obvious from the accompanying drawing which shows the invention applied for performing a polarity responsive function in which the device derives all of its energizing current from a single pair of inlet wires.

In the drawing, corresponding to Fig. 22 of the parent application, the electro-responsive structure embodying the present invention is shown at the left, whereas the electro-responsive structure shown at the right and including the coil 160 is

merely shown incidentally and is shown connected in series with the winding 150 and may, if desired, be disregarded or assumed omitted from the disclosure. When omitted it is merely removed from the circuit of coil 150.

As shown the core structure of the electro-responsive device comprises a closed U-shaped magnetic circuit portion of soft iron including a back yoke 157 and legs 151 and 152 which terminate in pole pieces 153 and 154, respectively, and which core structure is shunted by a soft iron bridge 155. This structure therefore includes a closed magnetic circuit comprising the back yoke 157 and the bridge 155 with portions of the legs 151 and 152 in series. An armature G preferably pivoted at one end, as shown, is in magnetic cooperative relationship with the pole pieces 153 and 154 by bridging the same as shown. This armature G is so spaced from the pole pieces 153 and 154 and is provided with such residual pin or residual stop structure that the relay will function only if magnetomotive forces of proper value and polarity are set up in both core portions 155 and 157. For this purpose windings or coils 148, 149 and 150 have been provided. The coil or winding 150 supplies the magnetomotive force in the back yoke 157, whereas the coil or winding 148—149, which for convenience has been split into two parts, supplies the magnetomotive force in the magnetic bridge 155. The winding 148—149 could obviously be a single winding it having been shown split into two parts to protect the full-wave rectifier 158 against lighting and to bring this rectifier and the windings 150 and 160 energized thereby to an intermediate potential with respect to the inlet wires 161 and 162. The armature G may be provided with a movable contact 165 when the device is to be used as a relay and may in other instances be used to operate other devices, such for instance, as a signal spectacle as shown in the parent application.

If the minus terminal of a direct current source is connected to the wire 161 and the plus terminal of such current source is connected to the wire 162, as conventionally shown, the closure of the circuit as by the depression of push button 156 will cause current to flow from the plus (+) terminal of said source through coil 148, the lower right-hand rectifying element of rectifier 158, coil 160, coil 150, upper left-hand rectifying element of rectifier 158, coil 149, push button 156, wire 161, to the minus (—) terminal of the source. The flow of this current will cause magnetomotive forces to be set up as

indicated by the solid arrows in coils 160 and 150 and as indicated by dotted arrows in coils 148 and 149 and since the magnetomotive forces as set up in back yoke 157 and bridge 155 act in multiple upon the armature G no magnetic shunting or sucking action will take place and the armature G will pick up providing that the current is equal to or larger than the pick-up current for the electromagnet. If now, on the other hand, the plus (+) terminal of such source is connected to the wire 161 and the minus (-) terminal of such source is connected to the wire 162 depression of the push button 156 will cause current to flow through a circuit in a direction which may be traced from terminal (+), wire 161, push button 156, coil 149, upper right-hand rectifying element of rectifier 158, coil 160, coil 150, lower left-hand rectifying element of rectifier 158, coil 148, wire 162, to the terminal (-) of the source. Obviously, the direction of the magnetomotive force in the magnetic bridge 155 will be in the opposite direction as indicated by the solid arrows whereas the direction of the magnetomotive force in the back yoke 157 and in the coil 160 will remain in the same direction as heretofore, namely, in the direction of the solid arrow so that in this case the magnetomotive forces set up in the back yoke 157 and the bridge 155 are in the same direction in the closed magnetic loop comprising these core portions 155 and 157 in series with portions of the legs 151 and 152. The magnetomotive force impressed across the poles 153 and 154 is therefore substantially zero and the armature G will not pick up.

In a structure of the type just described it is important that the armature G should not pick up as a result of the breaking of the circuit including the coils 150 and 160, for instance. If this should occur the resistance of the rectifier 158 would of course become very high, its out-put circuit being open, and for this reason among other reasons, less than normal current would flow in the coils 148 and 149 and the armature G would not pick up. Let us now assume, for the purpose of discussion only, that the coil 150 becomes short-circuited so that the resistance of the rectifier 158 is not increased and again in this case the armature G will not pick up because the magnetomotive force set up in the bridge 155 is shunted away from the armature G by the back yoke 157. In fact, the spaced and structural relationship between the armature G and the core structure 151, 152, 155, 157 is such that if double or even triple current is applied to either of the coils 148—149 or 150 the armature G will not pick up by reason of the fact that the magnetomotive force produced by such coil is substantially entirely shunted away by the shunting effect of the core portion on which the other coil is wound.

The structure described may of course exclude the electromagnet including coil 160, in which event the number of turns and size of wire employed in coil 150 is so chosen that the ampere turns flowing around back yoke 157 is substantially the same as it was prior to the removal of coil 160. Also in practice the ampere turns of both coils 148—149 and 150 are preferably approximately the same.

Having thus shown and described one specific embodiment of the invention and having described several ways in which the invention may be used it should be understood that the inven-

tion is not limited to these specific applications and that it may be used in other relations so long as the invention falls within the scope of the following claims.

5. What I claim is:

1. An electro-responsive device comprising, a soft iron core having a closed magnetic circuit divided into two magnetic core portions in series, a pole piece projecting from each of the two junctions of said magnetic core portions, a winding on each of said magnetic core portions, a full-wave rectifier deriving its energy from the circuit of one of said windings and applying its out-put energy to the other of said windings, whereby if said one winding is energized by direct current of either polarity the said other winding is always energized by current of one polarity, and an armature arranged to be in bridging relationship with respect to said pole pieces, whereby if said one winding is energized by direct current of one polarity said armature is attracted and if energized by current of the reverse polarity said armature remains retracted.
2. An electro-responsive device comprising; a soft iron core having a closed magnetic circuit divided into two magnetic core portions in series, a pole piece projecting from each of the two junctions of said magnetic core portions, a winding on each of said magnetic core portions, a full-wave rectifier having its in-put leads included in series in the circuit of one of said windings and having its out-put leads connected to the other of said windings, whereby if said one winding is energized by direct current of either polarity the said other winding is always energized by current of one polarity, and an armature arranged to bridge said pole pieces, whereby if said one winding is energized by direct current of one polarity said armature is attracted and if energized by current of the reverse polarity said armature remains retracted.
3. In an electro-magnetic device, an operating electro-magnetic structure having an operating winding, a pivoted armature disposed to be attracted through an airgap from a biased retracted position by the energization of said operating winding, a shunting electro-magnetic structure having a control winding, said shunting electro-magnetic structure being disposed so as to form a magnetic circuit of relatively low reluctance in multiple with the magnetic circuit of said electro-magnetic structure through said airgap and said armature, and means including a rectifier for connecting said operating and control windings together in a manner to render the energization of said control winding always in the same direction upon the energization of said operating winding, irrespective of the polarity of energization applied to said operating winding, whereby said armature is attracted only by energization of said device with a given polarity.
